STRAIN BAR ASSEMBLY

William L. Hollander, Centralia, Mo., assignor to
 A. B. Chance Company, Centralia, Mo., a corporation of Missouri

Application March 1, 1950, Serial No. 147,103

19 Claims. (Cl. 174—44)

1

The present invention relates to switch servicing equipment, and is particularly concerned with an improved switch equipment which is adapted to be isolated electrically from the line, while the line is still intact, so that the switch and its parts may be inspected, serviced, or replaced under de-energized conditions.

One of the objects of the invention is the provision of an improved switch of the tilting insulator type, the lead of which is so connected to a strain bar that it may be manipulated by means of insulated wrenches and clamp sticks so as to disconnect entirely the switch from the line at its lead, thus de-energizing the switch and permitting the linemen to work upon the switch without danger.

Another object of the invention is the provision of an improved switch assembly, including pivoted links for supporting the lead which extends from the line to a contact on a pivoted insulator, in which the strain bar, by means of which the line is attached to a string of insulators, is provided with a pivot flange for the links and for also acting as a connector which can be removed by loosening a few clamping bolts and lifting it with a clamp stick to de-energize the switch.

Another object of the invention is the provision of an improved switch structure of the class described, in which the combined connector plate and pivot plate for the lead and links can be readily replaced and secured electrically to a strain bar which is attached to the end of the line, thereby connecting a switch in circuit with the line again by means of hot line tools.

Other objects and advantages of the invention will be apparent from the following description and the accompanying drawings, in which similar characters of reference indicate similar parts throughout the several views.

Referring to the drawings, of which there are three sheets.

Fig. 1 is a side elevational view of a switch structure forming a part of a line installation and located at the top of a line pole, shown with a jumper attached, by means of which the switch is to be by-passed;

Fig. 2 is a similar view, showing the arrangement of the parts after the lead and links have been disconnected from the strain bar, for the purpose of isolating the switch electrically and de-energizing it while it is being serviced;

Fig. 3 is a fragmentary side elevational view of the strain bar connector and pivot plate which is used at the right hand end of the assembly of Fig. 1;

2

Fig. 4 is a side elevational view of the strain bar;

Fig. 5 is a sectional view, taken through the strain bar on the plane of the line 5—5 of Fig. 4, looking in the direction of the arrows;

Fig. 6 is a fragmentary sectional view, taken through the strain bar, on the plane of the line 6—6 of Fig. 3, looking in the direction of the arrows;

Fig. 7 is a fragmentary sectional view, taken on the plane of the line 7—7 of Fig. 3, looking in the direction of the arrows.

Referring to Fig. 1, 10 indicates in its entirety the switch assembly, which is mounted upon a line pole 11 by being secured to a pair of cross arms 12, 13. The switch is supported upon a channelled metal member 14 and is secured to the cross arms by bolts 15 passing through the cross arms and channel.

10 The present switch has its channelled base insulated from the line by a string of insulators 16 on the left and another string of insulators 17 on the right, these insulators being pivoted together and pivotally attached to the channel base 14 to withstand the tension of the line.

15 The end of the insulator string at the left insulator 16 pivotally supports a universal strain clamp 18 provided with an oval body 19 having a peripheral groove so arranged that the line 20 may pass about the strain clamp, beginning at the top side and, following the groove, it may pass under a clamping member 21, which is driven into clamping engagement with the line conductor by a screw bolt 22.

20 The conductor having traversed the strain clamp, it then extends upward at 23 and is bent over to be secured to the clamp or connector 24, which is carried by the fixed contact and fixed insulator. The channelled base 14 supports one or more fixed columns 25 which carry the insulator 26 by means of which the fixed contacts 27 are insulated from their surroundings.

25 The insulator 26 has a metal plate 28 at its upper end, by means of which the fixed contacts 27 are mounted on the insulator 26. The fixed contacts are integrally joined to a suitable electrical connector 29, which in this case engages the line conductor 23 to complete the circuit.

30 The switch contacts 27, visible in Fig. 1, are identical with other contacts mounted on the opposite side of the switch arm 30.

35 Connector plates 24 and 29 are located to receive conductor 23, about which they may be tightened by drawing the plate 24 down close to the terminal 29.

The base 31 of the contacts 27 carries a threaded member 32 engaging clamping plate 33 for clamping the upwardly extending arcing horns 34. The arcing horns 34, which are identical on both sides of the base 31, are bent outwardly at 35 so that their diverging ends 36 separate from the movable arcing horn 37 when it moves up past the bend 35.

The contacts 27 are provided with outwardly diverging U-shaped guides 38 to provide a tapered opening for receiving the switch blade 30.

The base 14 carries a pair of hangers 39 secured to it by bolts and provided with aligned bearings 40 for rotatably supporting the shaft 41. The insulator base 42 is mounted on the shaft 41 and has a downwardly projecting arm 43, which is pivotally connected at 44 to a connecting rod 45.

The connecting rod is connected to the crank arm 46 through a pair of pivots 47, 48, and an intermediate link 49, the pivots 47, 48 being at right angles to each other to form a universal connection.

The crank arm 46 is pivotally mounted on a shaft 50 carried by hanger 51; and crank arm 46 has a cooperating clamp 52 secured by two threaded bolts 53, 54 to the crank arm 46. The crank arm 46 and clamp 52 have a rectangular recess 55 between them for receiving an eccentric shaft, by means of which a plurality of switches are simultaneously actuated by the same shaft.

All of the details of the switch itself and its actuating means may be substantially as described in the prior patent of Leonard J. Linde, No. 2,489,426, issued November 29, 1949.

The insulator 56 has a metal cap, to which is secured the switch blade 30, to be moved by the insulator 56 on the shaft 41. The blade 30 has a clamping member 57 with a screw bolt 58 for securing the arcing horn 37 to the blade.

The movable switch member 30 is connected to the line by means of a flexible conductor or lead 59, one end of which is clamped to the switch blade 30 by a connector plate 60 and screw bolts 61. The other end of the lead 59 is clamped to a combined pivot plate and connector 62 by means of the bolts 63, clamping plate 64, and nuts 65.

Clamping plate 64 consists of a metal plate, which may be rectangular in shape, having bores for passing the bolts 63, and having suitable grooves extending longitudinally between the bores for receiving one or more conductors 59. The lead 59 is supported and guided by means of a plurality of rigid links 66, 67, the links having a plurality of clamping members 68 for holding the lead in substantially the position shown in Fig. 1, to move with the links.

The links are arranged in pairs so that there are two links 66, the left end of both links being pivoted on the movable switch blade 30 by a screw bolt 69; and the conductor is arranged between the links. At their opposite end, that is, the right end, the two links 66 are pivoted together by a bolt 70 carrying a cotter pin on the end opposite to its head.

The links 67 are pivoted at their upper end at 70; and at their lower end links 67 are arranged on the opposite sides of the combined connector and pivot plate 62, as shown in Fig. 6, where they are pivoted upon an eye bolt 71. The eye bolt 71 has a ring 72 large enough to be manipulated by means of an ordinary insulated clamp stick; and

at its opposite end the shank 73 carries a cotter pin 74.

In addition to the links 66 being secured together in parallel relation by the pivot bolts 69 and 70, and the links 67 being secured in a similar manner by bolts 70 and 71, these links may also be made more rigid by a plurality of through bolts 75, each of which has a head at one end and a cotter pin at the other end, with a tubular spacer between the links.

The combined pivot plate and connector 62 is a very important feature of the present invention; and it is shown in elevation in Fig. 6. It comprises an elongated metal plate having a rectangular body 76 provided with a pair of through bores 77 for the bolts 63. At its upper end plate 62 is formed with a cylindrical hinge formation 78 having a cylindrical through bore 79 forming a bearing for the shank 73 of the eye bolt 71.

The clamping plate 64, which secures the conductors 59 to the connector 62, also has bores for the bolts 63; and the bolts 63 carry spring washers 80 and nuts 65.

At its lower end the connector plate 62 has a parallel sided, axially extending slot 82. This slot is of sufficient width to pass the shanks of bolts 83, and is open at its lower end, as indicated at 84.

The plate has the two legs 85 beveled at 86 at the lower end (Fig. 6) for a purpose further to be described. The slot 82 is also adapted to receive the web 88 of the strain bar 89; and the web 88 at this point is beveled on both sides at its upper edge at 90, forming a V-shaped edge 91 for more readily guiding the web 88 into the open end 84 of the slot 82.

The strain bar 89 may consist of a cast metal member which is formed at its right end with a flat body 92, having a through bore 93 for attachment to a strain clamp 94. The strain clamp 94 may be substantially the same as the strain clamp 18 at the other end of the assembly (Fig. 1); and it is secured to the strain bar 89 by a through bolt 95 with a cotter pin in the end of the bolt.

The line conductor 96 may enter the groove 97 of the strain clamp 94 at its lower side, and may be curved about the body of the strain clamp in a clockwise direction, as shown in Fig. 1, until it emerges from the groove with a downwardly extending portion 98, which is clamped to the strain clamp by means of clamping member 99 and the bolt and nut 100.

The downwardly extending portion 98 of the line conductor is bent upward at 101 and has its end 102 clamped between the terminal pad 103 and the clamping member 104 by means of the screw bolts 105 threaded into clamping member 104.

Clamping member 104 is provided with a suitable longitudinally extending groove 106 for receiving the end 102 of the line conductor and effecting an electrical connection.

The terminal pad 103 comprises a rectangular metal member having four through bores 107 symmetrically arranged at its lower end for receiving the clamping bolts 105. At its upper end terminal pad 103 is beveled at 108 on the right hand side, as contrasted with the bevel 86 on the pivot plate 62, which is on the left hand side.

The upper end of the terminal pad 103 may have a longitudinally extending slot 109 for receiving the lower edge of the strain bar and web 88. Between its ends terminal pad 103 has a pair of centrally located bores 110 arranged in a

line and located to receive the screw bolts 83, which are preferably provided with spring washers 111 between the heads and the terminal pad 103.

The strain bar 89 is shown in elevation in Fig. 4, in cross section in Fig. 5, and in the assembly in Fig. 3. It comprises a cast metal member having a substantially rectangular body in elevation; and at its right end the body has a depending lug 112. This lug 112 extends downwardly and diagonally toward the right in Fig. 4; but may be placed at any desired angle.

The lug 112 is relatively thick, to provide sufficient body for the threads in the two transversely extending threaded bores 113.

The web 88 is relatively thin, like a metal plate, as shown in Fig. 6; and it is bordered on the body by means of a peripheral reinforcing flange 114 on both sides of the strain bar. Flange 114 may project until its outer surface is substantially flush with the surface of the flat body 92 at the right end of the strain bar 89.

As viewed from the top or right, the lug 112 (Fig. 5) tapers toward the top and where its edges join with a diagonal reinforcing and guide flange 115; and the lug 112 is oval at its lower end and provided with the tubular portions 116 surrounding the threaded bores 113. These tubular portions are joined by a reinforcing web 117.

The web 88 of the strain bar is also continued toward the left of the diagonal guide flanges 115, where it is slightly thickened, as indicated at 88a; and it is bordered on both sides of the strain bar by a diagonally extending guide flange 118 so that the flanges 118, 115 form an upwardly and downwardly diagonal slot on each side of the strain bar, these slots being indicated at 119.

The strain bar 89 has a further web portion 88b to the left of the guide flange 118 (Fig. 4); and this is bordered at the top and bottom by laterally projecting reinforcing flanges 120, 121. These may taper toward the left, as shown in Fig. 5, to the point 122, where they are again widened to join to a pair of parallel pivot flanges 123.

These parallel pivot flanges are separated by a rectangular slot 124, which is open at the left end; and the parallel flanges have the aligned bores 125. The two parallel flanges 123 fit on the opposite sides of the metal fitting 126 carried by insulator 17, to which they are pivotally secured by a through bolt 127, having a cotter pin in the end opposite to the head.

The strain bar 89 is identical in construction on its two opposite sides, as shown in Fig. 4.

At their upper ends the juncture between the flanges 118 and 120 is rounded at 128. The upper juncture between the flange 115 and the flange 114 is rounded at 129. This provides an upwardly diverging opening between these flanges for guiding the beveled end 86 of the pivot plate 62 into the slots 119.

The depending lug 117 is also preferably provided on its left side with a longitudinally extending, rectangular rib 130, which forms an extension of the thickened web portion 88a (Fig. 5) and aids in maintaining the alignment of the connector plate 62.

At the lower part of the strain bar 89 the flanges 121 and 118 are formed with an angular recess 131 at their juncture for the purpose of providing space for the beveled end 108 of the terminal pad 103 (Fig. 7).

The screw bolts 83 pass through the bores 110 of the terminal pad 103, and are threaded into the threaded bores 113 on the depending lug 112

carried by the strain bar. The ends of bolts 83 opposite to their heads are riveted over at 132 so that these bolts are never wholly removed; but there is sufficient clearance between the rivet ends 132 and the depending lug 112 so that the bolts 83 may be retracted to remove the clamping action of these bolts from the connector plate 62.

However, even at this time the bolts 83, passing through bores 110, continue to hold the terminal pad 103 loosely.

The operation of the present mechanism and the mode of its use in servicing the switch is as follows:

Referring to Fig. 1, a jumper conductor 133, which is heavily insulated, has its ends attached to the tap clamps 134, 135. The tap clamps are lifted by means of insulated clamp sticks, which are attached to the eyes of the eye screws 136; and one tap clamp 134 is secured to the line conductor 96 to the right of the switch assembly in Fig. 1.

The jumper 133 is put in good electrical connection with the line 96 by driving the eye screw 136 home. Then the second tap clamp 135 is similarly connected to the line conductor 20 by using a clamp stick. The switch assembly is now bypassed by the jumper 133; but the switch is still energized.

The portion 23 of the line conductor 20 is next 30 detached at the connector 24 by means of an insulated wrench socket carried by a wooden pole; and the conductor portion 23 is bent over toward the left, away from the switch assembly, as shown in Fig. 2. This disconnects the switch 35 from the line at the left.

The lineman then applies a socket wrench carried by an insulating wooden pole to the heads of the screw bolts 83, and withdraws these screw bolts until the tension of the spring washers 111 is relieved and the terminal pad 103 hangs loosely, but is carried by screw bolts 83, spaced from the face of the depending lug 112.

By virtue of the diagonal position of the lug 112 the terminal pad 103 tends to drop toward the left toward the heads of the bolts 83, leaving a wider space between the terminal pad 103 and lug 112.

The combined pivot plate and connector plate 62 is now no longer clamped at its lower end by the bolts 83; and a clamp stick is applied to the ring 72 of the eye bolt 71 by having its jaws closed through the ring. The operator may then lift the clamp stick 137 by means of its wooden pole; and acting upon the eye bolt 71, the tool end of the clamp stick may be used to slide the plate 62 off the web 88a and out of the slots 119, which are defined by the flanges 115, 118.

The slot 82 of plate 62 then passes upward off the bolts 83 and web 88a until it is totally disconnected from the strain bar 89, as shown in Fig. 2. The links 67 may then be pivoted over toward the left to the dotted line position of Fig. 2; and the clamp stick 137 may have its wooden pole secured in that position, holding the eye bolt 71 by fastening the lower end of the clamp stick to the line pole with a suitable saddle and pole clamp, such as is used for securing such operating poles to the line pole 11.

The lead 59 being secured to the plate 62, its lower end is moved with the connector plate 62; and the switch is now totally disconnected from the right side of the line 96 at the strain bar 89. Electric service through the line continues through the jumper 133; but the switch has been disconnected from the line at both ends and is

de-energized. It may now be serviced by the linemen as required and new parts substituted or repairs made on any part that requires service.

After the switch has been put in good condition again, the lower end of the clamp stick is released from the line pole 11 at the saddle which is holding it; and the lineman then moves the plate 62 over to the right hand position of Fig. 2 by means of the clamp stick 137 and brings the beveled end 86 of plate 62 down to the diverging openings of the slot 119 on the strain bar 89.

The slot 82 of plate 62 must be made to straddle the web 88a, but it is guided by the V-shaped point 91 of this web; and the plate 62 passes downward in the slots 119, being manipulated by the clamp stick. As the beveled end 86 of plate 62 approaches the beveled end 108 of terminal pad 103 the two opposite bevels guide the plate 62 between the terminal pad 103 and the depending lug 112 of the strain bar 89 until plate 62 again reaches the position of Fig. 3 or Fig. 6.

Then the bolts 83 are again tightened by means of an insulated socket wrench; and bolts 83 clamp the plate 62 in the strain bar in the position of Fig. 3. When this has been done, the switch is mechanically and electrically connected to the strain bar 89 at the right end of the switch assembly (Fig. 1).

The line conductor 23 is then again manipulated by means of the insulated clamp sticks into position in the connector 24; and the connector bolts are again tightened by means of an insulated socket wrench.

The switch is now again connected in circuit and should be closed before removing the jumper 133. The jumper 133 may now be removed by using a clamp stick to release the tap clamps 134 and 135; and the jumper is lifted from the line by means of the two clamp sticks, leaving the switch connected in circuit.

It will thus be observed that I have invented an improved switch assembly and improved servicing equipment whereby such a line switch may be electrically disconnected from the line at the strain bar at the same time the links are mechanically disconnected, which links support the switch lead.

The switch may then be serviced without interruption in the supply of electrical current; and all of the parts may be manipulated by means of tools carried by long wooden insulated poles, such as clamp sticks or other tools mounted on the well known "Universal" pole.

The present equipment is simple in construction, easy to release and easy to re-assemble by using a clamp stick; and the equipment is safe to manipulate in this manner.

While I have illustrated a preferred embodiment of my invention, many modifications may be made without departing from the spirit of the invention, and I do not wish to be limited to the precise details of construction set forth, but desire to avail myself of all changes within the scope of the appended claims.

Having thus described my invention, what I claim as new and desire to secure by Letters Patent of the United States, is:

1. A strain bar assembly for detachably supporting switch leads and the links which carry the leads, comprising a strain bar formed with bearing flanges at its opposite ends, for attachment by means of pintles to an insulator and to a strain clamp carrying the line, the said strain bar being provided, intermediate its ends, with upwardly and downwardly extending guide

means, means for electrically connecting the end of the line to the strain bar, and a combined pivot and connector plate electrically secured to a lead to the switch and pivotally secured to one of said links to provide a support for a link supporting said lead, said combined plate engaging said guide means on said strain bar to effect a mechanical and electrical connection.

2. A strain bar assembly for detachably supporting switch leads and the links which carry the leads, comprising a strain bar formed with bearing flanges at its opposite ends, for attachment by means of pintles to an insulator and to a strain clamp carrying the line, the said strain bar being provided, intermediate its ends, with upwardly and downwardly extending guide means, means for electrically connecting the end of the line to the strain bar, and a combined pivot and connector plate electrically secured to a lead to the switch and pivotally secured to one of said links to provide a support for a link supporting said lead, said combined plate engaging said guide means on said strain bar to effect a mechanical and electrical connection, said strain bar carrying threaded clamping members for clamping the combined plate when it has been engaged by said guide means.

3. A strain bar assembly for detachably supporting switch leads and the links which carry the leads, comprising a strain bar formed with bearing flanges at its opposite ends, for attachment by means of pintles to an insulator and to a strain clamp carrying the line, the said strain bar being provided, intermediate its ends, with upwardly and downwardly extending guide means, means for electrically connecting the end of the line to the strain bar, and a combined pivot and connector plate electrically secured to a lead to the switch and pivotally secured to one of said links to provide a support for a link supporting said lead, said combined plate engaging said guide means on said strain bar to effect a mechanical and electrical connection, said combined plate being provided with an eye for engagement with a clamp stick so that the combined plate and its attached parts may be removed from the strain bar by means of an insulated clamp stick.

4. A strain bar assembly for detachably supporting switch leads and the links which carry the leads, comprising a strain bar formed with bearing flanges at its opposite ends, for attachment by means of pintles to an insulator and to a strain clamp carrying the line, the said strain bar being provided, intermediate its ends, with upwardly and downwardly extending guide means, means for electrically connecting the end of the line to the strain bar, and a combined pivot and connector plate electrically secured to a lead to the switch and pivotally secured to one of said links to provide a support for a link supporting said lead, said combined plate engaging said guide means on said strain bar to effect a mechanical and electrical connection, said combined plate being provided with an eye for engagement with a clamp stick so that the combined plate and its attached parts may be removed from the strain bar by means of an insulated clamp stick, the said guide means comprising a web carried by the strain bar, and a longitudinal slot opening into the end of the combined plate.

5. A strain bar assembly for detachably supporting switch leads and the links which carry the leads, comprising a strain bar formed with bearing flanges at its opposite ends, for attachment by means of pintles to an insulator and to

a strain clamp carrying the line, the said strain bar being provided, intermediate its ends, with upwardly and downwardly extending guide means, means for electrically connecting the end of the line to the strain bar, and a combined pivot and connector plate electrically secured to a lead to the switch and pivotally secured to one of said links to provide a support for a link supporting said lead, said combined plate engaging said guide means on said strain bar to effect a mechanical and electrical connection, said combined plate being provided with an eye for engagement with a clamp stick so that the combined plate and its attached parts may be removed from the strain bar by means of an insulated clamp stick, the said guide means comprising a web carried by the strain bar, and a longitudinal slot opening into the end of the combined plate, and the strain bar also having border flanges on both sides of the web engaging both sides of the combined plate.

6. A strain bar assembly for connecting the line to insulators at a switch installation or the like, comprising a strain bar provided at its opposite ends with transverse bearing bores for receiving pins for connection to an insulator at one end and to a strain carrier at the other end, said body having a depending connector flange provided with a pair of transverse threaded bores, a threaded member in each bore, and a terminal pad, said terminal pad having a pair of bores for passing said threaded members, and said terminal pad having an electrical connector, and a combined connector and pivot plate adapted to be slid between the terminal pad and the depending lug and clamped by said threaded members, so that the combined plate may be secured to the strain bar or released from the strain bar by tightening or releasing said threaded members.

7. A strain bar assembly for connecting the line to insulators at a switch installation or the like, comprising a strain bar provided at its opposite ends with transverse bearing bores for receiving pins for connection to an insulator at one end and to a strain carrier at the other end, said body having a depending connector flange provided with a pair of transverse threaded bores, a threaded member in each bore, and a terminal pad, said terminal pad having a pair of bores for passing said threaded members, and said terminal pad having an electrical connector, and a combined connector and pivot plate adapted to be slid between the terminal pad and the depending lug and clamped by said threaded members, so that the combined plate may be secured to the strain bar or released from the strain bar by tightening or releasing said threaded members, said depending lug extending slightly diagonally so that the heads of the threaded members are lowermost and the terminal pad tends to rest against said heads, leaving a space between the terminal pad and the depending lug for easy insertion of the combined plate.

8. A strain bar assembly for connecting the line to insulators at a switch installation or the like, comprising a strain bar provided at its opposite ends with transverse bearing bores for receiving pins for connection to an insulator at one end and to a strain carrier at the other end, said body having a depending connector flange provided with a pair of transverse threaded bores, a threaded member in each bore, and a terminal pad, said terminal pad having a pair of bores for passing said threaded members, and said termi-

nal pad having an electrical connector, and a combined connector and pivot plate adapted to be slid between the terminal pad and the depending lug and clamped by said threaded members, so that the combined plate may be secured to the strain bar or released from the strain bar by tightening or releasing said threaded members, said depending lug extending slightly diagonally so that the heads of the threaded members are lowermost and the terminal pad tends to rest against said heads, leaving a space between the terminal pad and the depending lug for easy insertion of the combined plate, the said combined plate and terminal pad being oppositely beveled at their leading ends, which approach each other to guide the combined plate between the terminal pad and depending lug.

9. A strain bar assembly for connecting the line to insulators at a switch installation or the like, comprising a strain bar provided at its opposite ends with transverse bearing bores for receiving pins for connection to an insulator at one end and to a strain carrier at the other end, said body having a depending connector flange provided with a pair of transverse threaded bores, a threaded member in each bore, and a terminal pad, said terminal pad having a pair of bores for passing said threaded members, and said terminal pad having an electrical connector, and a combined connector and pivot plate adapted to be slid between the terminal pad and the depending lug and clamped by said threaded members, so that the combined plate may be secured to the strain bar or released from the strain bar by tightening or releasing said threaded members, the said combined plate being formed with a longitudinal slot extending into its end, and the said strain bar having a complementary central portion for engaging the opposite sides of said slot as the combined plate is moved into place.

10. A strain bar assembly for connecting the line to insulators at a switch installation or the like, comprising a strain bar provided at its opposite ends with transverse bearing bores for receiving pins for connection to an insulator at one end and to a strain carrier at the other end, said body having a depending connector flange provided with a pair of transverse threaded bores, a threaded member in each bore, and a terminal pad, said terminal pad having a pair of bores for passing said threaded members, and said terminal pad having an electrical connector, and a combined connector and pivot plate adapted to be slid between the terminal pad and the depending lug and clamped by said threaded members, so that the combined plate may be secured to the strain bar or released from the strain bar by tightening or releasing said threaded members, the said strain bar being formed with a central longitudinally extending web and with guide flanges extending in the direction of the terminal pad, to engage both sides of the combined plate and to guide it into place.

11. A strain bar assembly for connecting the line to insulators at a switch installation or the like, comprising a strain bar provided at its opposite ends with transverse bearing bores for receiving pins for connection to an insulator at one end and to a strain carrier at the other end, said body having a depending connector flange provided with a pair of transverse threaded bores, a threaded member in each bore, and a terminal pad, said terminal pad having a pair of

of bores for passing said threaded members, and said terminal pad having an electrical connector, and a combined connector and pivot plate adapted to be slid between the terminal pad and the depending lug and clamped by said threaded members, so that the combined plate may be secured to the strain bar or released from the strain bar by tightening or releasing said threaded members, the said two threaded members being riveted over at their outer ends on the opposite side of said depending lug, so that they cannot be removed from the depending lug, thereby keeping the terminal pad in position to be engaged by the combined plate.

12. A strain bar assembly for connecting the line to insulators at a switch installation or the like, comprising a strain bar provided at its opposite ends with transverse bearing bores for receiving pins for connection to an insulator at one end and to a strain carrier at the other end, said body having a depending connector flange provided with a pair of transverse threaded bores, a threaded member in each bore, and a terminal pad, said terminal pad having a pair of bores for passing said threaded members, and said terminal pad having an electrical connector, and a combined connector and pivot plate adapted to be slid between the terminal pad and the depending lug and clamped by said threaded members, so that the combined plate may be secured to the strain bar or released from the strain bar by tightening or releasing said threaded members, the said combined plate being provided with threaded members and a clamping connector plate for securement to an electrical conductor, and also having a pivotal connection to a mechanical link which supports said conductor.

13. A strain bar assembly for connecting the line to insulators at a switch installation or the like, comprising a strain bar provided at its opposite ends with transverse bearing bores for receiving pins for connection to an insulator at one end and to a strain carrier at the other end, said body having a depending connector flange provided with a pair of transverse threaded bores, a threaded member in each bore, and a terminal pad, said terminal pad having a pair of bores for passing said threaded members, and said terminal pad having an electrical connector, and a combined connector and pivot plate adapted to be slid between the terminal pad and the depending lug and clamped by said threaded members, so that the combined plate may be secured to the strain bar or released from the strain bar by tightening or releasing said threaded members, the said combined plate being provided with threaded members and a clamping connector plate for securement to an electrical conductor, and also having a pivotal connection to a mechanical link which supports said conductor, the said pivotal connection including an eye bolt which may be safely engaged and handled by means of an insulated clamp stick.

14. A strain bar assembly for detachably supporting a switch lead and its supporting link, comprising a strain bar provided with an eye at each end for attachment to an insulator and to a strain clamp, a combined pivot plate and connector, comprising a plate formed with a bearing at one end for supporting said link, said plate also supporting an electrical connector connected to said switch lead and carried by said plate, an electrical connector carried by said strain bar for connection to the line, guide means

carried by said strain bar for guiding said plate into a position in which it is to be clamped to the strain bar, and threaded means carried by the strain bar for clamping said plate in said position.

15. A strain bar assembly for electric transmission lines, comprising a strain bar having means at its ends for strain connection to an insulator and to a line strain clamp, an electrical connector carried by the strain bar for connection to the line which is to be carried by the strain clamp, a combined connector and pivot plate removably secured on said strain bar, said plate carrying an electrical connector for connection to a flexible conductor which is to be connected to the other end of the line, a link for supporting said flexible conductor, pivotally mounted on said pivot plate, and clamping means for securing the combined connector and pivot plate on the strain bar, to effect a mechanical and electrical connection or disconnection of the link and flexible conductor from the strain bar simultaneously.

16. A strain bar assembly for electric transmission lines, comprising a strain bar having means at its ends for strain connection to an insulator and to a line strain clamp, an electrical connector carried by the strain bar for connection to the line which is to be carried by the strain clamp, a combined connector and pivot plate removably secured on said strain bar, said plate carrying an electrical connector for connection to a flexible conductor which is to be connected to the other end of the line, a link for supporting said flexible conductor, pivotally mounted on said pivot plate, and clamping means for securing the combined connector and pivot plate on the strain bar, to effect a mechanical and electrical connection or disconnection of the link and flexible conductor from the strain bar simultaneously, the said combined connector and pivot plate being connected to said link by means of an eye bolt serving as a pintle, the eye bolt also being used to manipulate the pivot plate during its removal and attachment by means of a clamp stick or the like.

17. A strain bar assembly for electric transmission lines, comprising a strain bar having means at its ends for strain connection to an insulator and to a line strain clamp, an electrical connector carried by the strain bar for connection to the line which is to be carried by the strain clamp, a combined connector and pivot plate removably secured on said strain bar, said plate carrying an electrical connector for connection to a flexible conductor which is to be connected to the other end of the line, a link for supporting said flexible conductor, pivotally mounted on said pivot plate, and clamping means for securing the combined connector and pivot plate on the strain bar, to effect a mechanical and electrical connection or disconnection of the link and flexible conductor from the strain bar simultaneously, the said clamping means comprising a depending supporting lug carried by the strain bar and provided with threaded means, said threaded means carrying the first-mentioned electrical connector and serving as a clamp for clamping the pivot plate against said lug.

18. A strain bar assembly for electric transmission lines, comprising a strain bar having means at its ends for strain connection to an insulator and to a line strain clamp, an electrical connector carried by the strain bar for connec-

tion to the line which is to be carried by the strain clamp, a combined connector and pivot plate removably secured on said strain bar, said plate carrying an electrical connector for connection to a flexible conductor which is to be connected to the other end of the line, a link for supporting said flexible conductor, pivotally mounted on said pivot plate, and clamping means for securing the combined connector and pivot plate on the strain bar, to effect a mechanical and electrical connection or disconnection of the link and flexible conductor from the strain bar simultaneously, said strain bar having a depending lug provided with a clamping surface, threaded members carried by said lug and carrying said clamping means, said combined connector and pivot plate being provided with a slot for embracing said threaded means and being insertable between said lug and clamping means to be clamped by said threaded means.

19. A strain bar assembly for electric transmission lines, comprising a strain bar having means at its ends for strain connection to an insulator and to a line strain clamp, an electrical connector carried by the strain bar for connection to the line which is to be carried by the strain clamp, a combined connector and pivot plate removably

secured on said strain bar, said plate carrying an electrical connector for connection to a flexible conductor which is to be connected to the other end of the line, a link for supporting said flexible conductor, pivotally mounted on said pivot plate, and clamping means for securing the combined connector and pivot plate on the strain bar, to effect a mechanical and electrical connection or disconnection of the link and flexible conductor from the strain bar simultaneously, said strain bar being provided with a depending lug and with a guide slot above said lug for receiving said pivot plate, said clamping means comprising a pair of threaded members and a terminal pad forming a part of said first-mentioned connector.
